UNITED STATES PATENT OFFICE.

ROBERT D. HICKOK, OF ATLANTA, GEORGIA.

ELECTRIC-CLOCK SYSTEM.

1,016,499.

Specification of Letters Patent.

Patented Feb. 6, 1912.

Application filed March 7, 1911. Serial No. 612,960.

To all whom it may concern:

Be it known that I, ROBERT D. HICKOK, a citizen of the United States, residing at Atlanta, in the county of Fulton and State of Georgia, have invented certain new and useful Improvements in Electric-Clock Systems, of which the following is a specification.

This invention relates to electric clock systems, and has for its object to provide an improved method of and means for setting the hands of a secondary clock, or synchronizing the same with the master clock, this object being effected by means controlled by reversing the direction of polarity of the current from the master clock.

In my pending application 563792 filed May 27, 1910, there is disclosed a secondary clock including a magnet and means controlled thereby to set the hands when the polarity of the magnet is reversed the magnet acting also as usual to operate the hands for indicating time.

The invention herein claimed includes the master clock and associated devices by means of which said secondary clock, or one adapted to operate in the same way, is actuated.

It is usual in electric clock systems to operate the hands of the secondary clock by means of impulses from the master clock, energizing an electromagnet which controls the movements of the hands of the secondary clock, the armature of the electromagnet being moved in one direction for this purpose by means of impulses transmitted by the master clock, said impulses being of one polarity. In the present system, this method of operation is retained for time marking purposes, but the master clock also operates to reverse the polarity of the current at stated periods, for the purpose of setting the hands of the secondary clock, or permitting them to be set.

The invention is illustrated in the accompanying drawings, in which—

Figure 1 is a partly diagrammatic view of the system, including the master and secondary clocks. Fig. 2 is a side view of part of the master clock. Fig. 3 is a partial front elevation of the secondary clock.

Inasmuch as the secondary clock is fully described in the application above referred to, the following brief description of its

construction and method of operation is all that is considered necessary for this application: The secondary clock has a permanent horse shoe magnet 8 between the branches of which is an electromagnet 9 which is energized by impulses from the master clock. The armature 10 of this magnet is pivoted upon an axis concentric with the arbor 11 of the minute hand 12, and said armature normally hangs vertically with its lower end between the poles 13 of the permanent magnet, which normally attract said end equally. When an impulse of one polarity is sent through the electromagnet the polarity of the armature is changed and it will swing in one direction and when an impulse of opposite polarity is sent through the electromagnet the polarity of the armature will be reversed and it will swing in the opposite direction. The lower end of the armature carries a pivoted pawl 14 which engages a minutes' ratchet 15 fast on the arbor 11 of the minute hand. By a suitable and well known train the movement of this arbor is reduced and transmitted to the hour hand 17. A spring detent 18 prevents back slip. By this means the time marking movements of the hands are produced, when the lower end of the armature swings to the left.

A heart shaped cam 19 is mounted on the quill of the hour hand and properly positioned to locate the hands at a predetermined point, say 12 o'clock, when the gearing controlling said hands is freed. This cam is pressed by a roller 20 carried by lever 21, which is pivoted at 22, the roller being pressed against the cam by a coiled spring 23 connected to the lever, the spring being of sufficient strength to turn the cam, and thereby the hands, until the roller runs to the notch in the cam, thereby setting the hands.

After the roller 20 passes the point of the cam in the normal operation of the clock, it is held out of contact with the cam, until released for the purpose of setting the hands. It will be understood that if the roller 20 continued to press on the cam after passing the point thereof (that is, after six o'clock if the hands are to be set at twelve o'clock) it would tend to cause the hands to creep or gain time, since the pressure of the spring 23 would tend to turn the hands forward instead of backward. As the hands and the

cam 19 are turned in consequence of the normal operation of the clock the roller will ride up the cam to the point thereof. As the lever 21 swings down in consequence of this action, it wipes against the toe 25 of a pivoted catch 26, and when the roller reaches the point of the cam the free end of the lever 21 passes below the catch, which then swings in until the toe engages the end of the lever; which is thus held by the catch until the latter is tripped.

The catch has near the lower end thereof a rearwardly projecting pin 30 located at one side of a spring 31 attached to the detent 18, and said spring depends in position to be struck by the head of the pawl 14 when said pawl is swung to the right in consequence of the vibration of the armature 10 in that direction. When the polarity of the magnet is reversed as above described it causes the lower end of the armature 10 to swing to the right, carrying with it the pawl 14 which is forced against the spring 31 and in consequence of the shape of the head of the pawl it is forced, by a cam action against said piece 31, out of engagement with the ratchet wheel 15, and the same movement carries the piece 31 to the right and releases the detent 18 from the ratchet wheel. The spring 23 then acts, and by reason of the pressure of the roller 20 against the cam, said cam turns carrying with it the hands, until the roller runs down to the low point or notch of the cam, thereby returning the hands to twelve o'clock, the setting point. If the hands have progressed beyond six o'clock before the setting action occurs the lever 21 will be caught by the catch 26, but when the setting time arrives the pawl 14 will be swung to the right as described, carrying with it the piece 31 which will then strike the pin 30 projecting from the catch and swing said catch to the right releasing the toe 25 from the end of the lever which, then, in consequence of the pressure of the spring 23, will be snapped up against the cam 19 and by pressure thereon will force the hands around clockwise to the setting position. The operation will be more fully apparent from the pending application above referred to.

For effecting the operation of the secondary clock as above described the following means are provided: A indicate the plates of the master clock, and B is a center post carrying the minute hand H which revolves once an hour. On the center post B is secured the usual cannon pinion C engaging wheel D which is mounted on pinion E which at its front end engages the hour wheel G connected to hour hand I by the usual quill. The inner end of the pinion E projects backwardly through the front plate of the clock and engages wheel F which is a duplicate of the hour wheel G. The pin-

ion E is supported in position by the bridges P and Q. As so far disclosed the description will apply to almost any clock, except the rear projection of the pinion E and the driving wheel F, and the movement may be driven in any suitable manner. Upon the hub of the wheel F and revolving with it is mounted a disk J and immediately back of this disk is a duplicate disk K which is secured to the center post B, and it will be seen that the two disks when driven will rotate in the same direction, and that disk J will make one revolution in twelve hours and disk K one revolution per hour. The disks J and K have notches R and S, which by the described rotation of said disks will be registered in the position shown in Fig. 1 once every twelve hours (assumed at twelve o'clock). An arm L is pivoted on a post M and has a projection T which rests upon the two disks and is adapted to drop into the notches of said disks when said notches are registered. The size of the notches is such that they will allow the arm L to fall about thirty seconds before twelve o'clock and will raise it again about thirty seconds after twelve o'clock. These periods of course may be varied, but are provided in order to give the secondary clock mechanism time to operate. The notches are beveled on one side so as to lift the projection T and arm L when the disks are rotated as usual. The disk K connected to the minute arbor will of course act as the lifter, because of its more rapid travel. The arm L is arranged to close a contact at the adjustable screw O, and this contact reverses the polarity of the magnet 9 by connections to be described.

X indicates, as a whole, a pole changing relay, which is illustrated in diagram, and may be of any suitable type, the coil V of which is connected in series with the master clock contacts represented by the arm L and the contact screw O. The pole changer X has four fixed contacts represented at 3, 4, 5 and 6, and two movable contacts shown at 1 and 2, and normally (that is at all times except 12 o'clock) point 1 is in contact with point 5 and point 2 in contact with point 6, this being the normal condition when the secondary clock hands are being advanced minute by minute. The minute circuit closing device of the master clock is indicated at W, connected on one side to the point 1 and on the other side to the battery U and point 2. The minute operating devices are not shown, as they are well known in the art and may be of any ordinary type. The points 3 and 4 of the pole changer are connected by wires 3^a and 4^a to the magnet 9 of the secondary clock. The point 3 is also connected by a cross connection 3^b to the point 6, and the point 4 by a cross connection 4^b to the point 5, and when the pole changer is in ordinary position an impulse

will be transmitted from the battery, at each closure of the contacts W, through said contacts on one side from the battery through the points 1, 3 and wire 3^a to the magnet 9, 5 and back through wire 4^a and contacts 4 and 2 to the battery.

At the setting time, that is at say thirty seconds before twelve o'clock, the connections to the secondary clock will be reversed 10 as follows: The arm L of the master clock by reason of the notches R and S in the cam-disk J and K being registered, will drop and make contact with the screw O, thus closing the bridged circuit from the battery 15 U through arm L, contact O and coil V to the battery. When the coil V is energized it will shift the movable member of the pole 20 changer, carrying the points 1 and 2 to the points 5 and 6, and from the points 3 and 4, 25 as indicated in dotted lines in Fig. 1, and in consequence of the cross connections 3^b and 4^b the impulse transmitted over the line 3^a, 4^a will be of reverse polarity, which reverse impulse will actuate the hand setting devices as above described. The contacts of 30 the pole changer will be held in this synchronizing position until say thirty seconds after twelve o'clock when the arm L will be lifted, the contact broken at O and the relay returned to original position by gravity or 35 by any suitable spring such as represented at Y. By the provision of a pole changer in the circuit between the master and secondary clocks, and by the other means described, the hand setting devices may thus be operated by reversing the current and

only a single magnet is necessary in the secondary clock.

Having thus described my invention, what I claim as new and desire to secure by Letters Patent is:—

1. In an electric clock system, the combination of primary and secondary clocks in a single circuit, a pole changer operated by the primary clock, in the circuit between said clocks, a magnet in said circuit, means controlled by impulses of one polarity in said magnet to operate the hands of the secondary clock to indicate time, and means controlled by impulses of opposite polarity 50 in said magnet to set the hands of the secondary clock.

2. In an electric clock system, the combination of primary and secondary clocks in circuit, a pole changer in said circuit, means automatically actuated by the master clock to operate the pole changer at definite times and reverse the polarity of the current in the circuit, a magnet in said circuit, means controlled by impulses of one polarity in 55 said magnet to operate the hands of the secondary clock to indicate time, and means controlled by impulses of opposite polarity 60 in said magnet to set the hands of the secondary clock.

In testimony whereof, I affix my signature in presence of two witnesses.

ROBERT D. HICKOK.
